UNITED STATES PATENT OFFICE.

WILLIAM STOLL, OF ASHTABULA, OHIO.

MACHINE FOR MAKING HAT-FRAMES.

No. 814,992.

Specification of Letters Patent.

Patented March 13, 1906.

Application filed August 12, 1905. Serial No. 273,866.

To all whom it may concern:

Be it known that I, WILLIAM STOLL, a citizen of the United States, residing at Ashtabula, Ashtabula county, State of Ohio, have invented new and useful Improvements in Machines for Making Hat-Frames, of which the following is a specification.

This invention relates to an improved machine for making wire hat-frames, the machine being so constructed that hat-frames of all conceivable contours may be made thereon.

In the accompanying drawings, Figure 1 is a plan of my improved machine for making hat-frames; Fig. 2, a vertical longitudinal section, partly in elevation, thereof; Fig. 3, a perspective view illustrating one form of a hat-frame made on the machine, and Fig. 4 is a detail.

20 The letter *a* indicates an upright spindle adapted to be rotatably secured to a support *b* by a clamp *c*. To spindle *a* is secured a collar or head *d*, having radially-projecting arms *d'*, to each of which is fulcrumed at *e'* a two-arm lever *e*. The levers *e* may be tilted on their fulcrums by a tubular slide *f*, movable on spindle *a* and having pins *f'*, that engage oblique slots *e''* of levers *e*. Thus when the slide is raised the upper ends of 25 levers *e* will converge, while when the slide is lowered such upper ends will diverge. The slide *f* is operated by a hand-lever *g*, received within a longitudinal groove *a'* of spindle *a* and pivoted to the latter at *a''*. Lever *g* has a curved finger *g'* engaging an opening *f''* of slide *f*, so that by tilting the lever the slide may be raised or lowered.

To the upper end of each lever *e* is adjustably secured a radially-extending arm or support *h*. The adjustment between the parts *e* and *h* is such that the arms *h* may be set at different angles to the levers *e*, to which effect the upper end of each lever *e* is provided with three, more or less, radial slots *e''* and with a bolt *e'* back of such slots. The inner end of each arm *h* has a longitudinal slot *h'*, adapted to engage bolt *e'*, and a laterally-extending pin *h''*, adapted to engage either one of the slots *e''*. Along each arm *h* 45 extends a spaced parallel plate *i*, connected thereto by a series of bolts *j*. Each arm *h*

carries at its inner end a hat-frame-crown support *k* and along its body a series of hat-frame-rim supports *l*. The supports *k* *l* are clamped to arm *h* by plate *i* and bolts *j*, so that the supports may be secured to the arms at various angles and at various elevations.

Each hat-crown support *k* consists of a doubled wire, to which is adapted to be clamped at different elevations a slide *m*, 60 having notch *m'*. The slide *m* serves to receive the top crown-wire *n*. At its lower end each support *k* is provided on each shank with a hook *k' k''*, adapted to receive the bottom crown-wire *o*. By employing either the outer 65 set of hooks *k'* or the inner set of hooks *k''* the slant of the hat-crown may be changed to conform to the size or fashion desired.

Each of the rim-supports *l* consists of a doubled wire the shanks of which straddle 70 bolts *j* between parts *h* and *i*. Each support *l* has at its upper end a hook *l'*, adapted to receive one of the rim-wires *p*. The length of each row of supports *l* increases preferably from the center outward.

75 In use the levers *e*, arms *h*, and supports *k* *l* are so adjusted as to produce a hat-frame of the desired shape and size. The top crown-wire *n* is laid around slides *m* and is connected at its ends, after which the radial 80 wires *q* are connected thereto. The bottom crown-wire *o* is laid around either set of hooks *k' k''* and is connected at its ends, and then the radial wires *q* are connected to wire *o*. In like manner the rim-wires *p* are successively laid around supports *l*, each wire being connected to the crown by the cross-wires *q*. In this way the frame is built up in a quick and simple manner. After the frame is finished the lever *g* is manipulated to raise 85 slide *f*, and thereby contract the upper ends of levers *e*, so that the supports *k* and *l* clear the frame and permit the latter to be raised off the hooks.

If double-rim hat-frames are to be made, a 90 notched slide *r* is mounted upon each of the rim-supports *l*, as shown in Fig. 4. The slides *r* are surrounded by the lower rim-wires *s*, secured to the frame-crown by the cross-wires *t*.

95 What I claim is—

100 In a machine for making hat-frames, the

combination of a rotatable spindle with a
slide, a series of levers engaged thereby, a
series of arms, means for adjustably securing
the arms to the levers, crown-supports and
5 rim-supports adjustably secured to the arms,
and slides mounted on the crown-supports
and rim-supports, substantially as specified.

Signed by me at New York city, (Manhat-
tan), New York, this 11th day of August, 1905.

WILLIAM STOLL.
